UNITED STATES PATENT OFFICE.

ALBERT GRIEVES, OF SPRINGFIELD, OHIO, ASSIGNOR TO INTERNATIONAL HARVESTER COMPANY, A CORPORATION OF NEW JERSEY.

BAND-BRAKE.

No. 799,728.

Specification of Letters Patent.

Patented Sept. 19, 1905.

Application filed May 17, 1905. Serial No. 260,908.

To all whom it may concern:

Be it known that I, ALBERT GRIEVES, a citizen of the United States, residing at Springfield, in the county of Clark and State of Ohio, have invented certain new and useful Improvements in Band-Brakes, of which the following is a specification, reference being had to the accompanying drawings, forming a part thereof.

This invention relates to brake mechanism applicable to hoisting-gear, and particularly to the hoisting mechanism applied to hay-stackers.

It consists in a base-piece having sheaves or band-wheels mounted thereon and a brake mechanism connected to one of the sheaves and operative to control the movement of the sheave and also a band or cable grip operative to prevent a too rapid movement of the hoisting-rope, the object of the invention being to provide a mechanism that may be conveniently manipulated and one that will be both powerful and effective in operation. These objects are attained by the mechanism illustrated by the accompanying drawings, in which—

Figure 1 is a top plan view of the brake mechanism. Fig. 2 is a side elevation of Fig. 1, and Fig. 3 is a detail of the operating-lever.

Like reference-numerals represent the same parts throughout the several views.

1 represents a portion of the bed-frame of a hay-stacker, 2 a base-plate secured thereto. Mounted upon the base-plate is a vertical sheave 3 and a horizontal sheave 4, the vertical sheave being arranged in a manner to receive the rope 5 from the horizontal one. The power is applied at the end 6 of the rope, and the end 7 is led to the secondary members of the hoisting mechanism. (Not shown.) Integral with the horizontal sheave 4 is a smooth-faced band-wheel 8. Pivotedly mounted on the base is a hand-lever 9, having an upwardly-projecting arm 10. Connected to the arm 10 is one end of a flexible band 11, that passes partially around the wheel 8 and has its opposite end secured to a vertically-disposed ear 12, forming part of the base 2, and connected to a depending portion 13 of the hand-lever and a plate 14, secured to the bed-frame, is a coiled spring 15 operative to yieldingly draw the lever toward the bed-frame and the flexible band around the wheel 8. Mounted on a vertical pivot 16 is an arm 17, having a roller 18 journaled thereon and

adapted to contact with the rope and draw it toward the horizontal sheave, and 19 is a toe-piece on said arm contacting with said rope when the arm has reached the limit of its inward swing and, pressing it against the sheave, frictionally resists the pull of the rope between the two surfaces. An earpiece 20 forms part of the arm 17 and is adapted to contact with the arm 10 of lever 9, as shown in Fig. 1.

When power is applied to the rope 6 to elevate the load, the arm 17 will swing about its pivot as the rope is drawn straight away from the sheave, as shown by dotted lines in Fig. 1, and the ear 20 engaging with the arm 10 will move lever 9 about its pivot and release the strain upon the flexible band 11. As soon as the load is discharged and the operative power is released from the rope 6 the flexible band is brought in contact with the wheel through the action of the spring 15 and the frictional resistance of the band is increased or diminished by means of the hand-lever 9. A coiled spring 21 surrounds the hub of the arm 17 and is operative between the arm and a fixed part of the base to hold the arm toward the horizontal sheave, and additional force is applied to the arm through its connection with the lever 9 to regulate the speed of the returning parts.

What I claim as my invention, and desire to secure by Letters Patent, is—

1. In a band-brake, the combination of a base-plate, a sheave journaled on said plate and having a projecting rim concentric therewith, a flexible band partially surrounding said rim and means for tightening said band, a power-transmitting rope engaging with said sheave, an arm pivotally mounted on said base, said arm having a roller rotatably mounted thereon and contacting with said rope to guide it toward the sheave, and a spring operative to swing the arm toward said sheave.

2. In a band-brake, the combination of a base-plate, a sheave journaled thereon, said sheave having a projecting rim concentric therewith, a flexible band partially surrounding said rim, a lever pivotally mounted on said base, one end of said band being connected to said lever and the opposite end to said base, a power-transmitting rope engaging with said sheave, an arm pivotally mounted on said base, said arm having a roller rotatably mounted thereon and contacting with

said rope to guide it toward the sheave, a spring operative to swing the arm toward the sheave, there being an ear upon the arm that contacts with said lever to move said arm in the same direction.

3. In a brake mechanism, the combination of a base-plate, a sheave journaled thereon, a power-transmitting rope engaging with said sheave, an arm pivotally mounted on said base, a roller, said roller journaled upon said arm and engaging with said rope to guide it toward the sheave, and a spring operative between said base and arm to swing the latter toward the sheave.

15 4. In a brake mechanism, the combination of a base-plate, a sheave journaled thereon, a power-transmitting rope engaging with said sheave, a brake-arm pivotally mounted on said base, a roller, said roller journaled upon said arm and adapted to engage with said rope and guide it toward said sheave, there being a toe-piece beyond the roller that contacts with the rope when the arm is moved toward the sheave.

25 5. In a brake mechanism, the combination of a base-plate, a sheave journaled thereon, a power-transmitting rope engaging with said sheave, a brake-arm having one end pivotally mounted on said base, a roller journaled upon the arm and engaging with the rope in a man-

ner to guide it toward the sheave, there being a toe-piece at the opposite end of said arm adapted to engage with the rope and hold it against the sheave when the arm is moved in that direction, and means for holding said toe against the rope.

6. In a band-brake mechanism, the combination of a base, a sheave journaled thereon, said sheave having a projecting rim concentric therewith, a flexible band partially surrounding said rim, a hand-lever pivotally mounted on said base, one end of said band being connected to said lever and the opposite end to said base, a coiled spring connected to said lever and the base and operative to move the lever in a direction to tighten the band, a power-transmitting rope engaging said sheave, a brake-arm pivotally mounted on said base and adapted to press the rope against said sheave, said arm contacting with said hand-lever in a manner to be moved toward the sheave when said hand-lever is operated to tighten said flexible band.

In witness whereof I hereto affix my signature in presence of two witnesses.

ALBERT GRIEVES.
